a corporation of West Virginia**

Application May 1, 1953, Serial No. 24,800

Term of patent 14 years

(Cl. D36—8)

To all whom it may concern:

Be it known that I, Louis W. Stenger, a citizen of the United States, residing at Morgantown, in the county of Monongalia and State of West Virginia, have invented a new, original, and ornamental Design for a Glass, of which the following is a specification, reference being had to the accompanying drawing, forming part thereof.

Figure 1 is a perspective view of a glass, showing my new design; and

Figure 2 is a developed plan view of the lateral surface thereof.

I claim:

The ornamental design for a glass, as shown.
LOUIS W. STENGER.
